COMBINED CIGARETTE LIGHTER AND ASH TRAY

Samuel J. Koch, ½ Korex Industries, 831 Malcolm
Road, Burlingame, Calif. 94010

Filed Aug. 4, 1970, Ser. No. 24,294

Term of patent 14 years

Int. Cl. D27—03

U.S. Cl. D85—2

FIG. 5

FIG. 1 is a top plan view of a combined cigarette lighter and ash tray, showing my new design;

FIG. 2 is a bottom plan view;

FIG. 3 is an exploded side elevational view, the opposite side being a mirror image of the side shown;

FIG. 4 is a sectional view taken substantially along the line 4—4 of FIG. 1; and

FIG. 5 is a top perspective view thereof.

I claim:

The ornamental design for a combined cigarette lighter and ash tray, as shown and described.
